UNITED STATES PATENT OFFICE.

WILLIAM WESTBURY, OF CANEY, KANSAS.

CYLINDER-CAPPING DEVICE.

Application filed January 19, 1922. Serial No. 530,479.

To all whom it may concern:

Be it known that I, WILLIAM WESTBURY, a citizen of the United States, residing at Caney, in the county of Montgomery and 5 State of Kansas, have invented new and useful Improvements in Cylinder-Capping Devices, of which the following is a specification.

This invention relates to electrical cylinder capping devices for use in "cracking" or severing glass cylinders into suitable lengths or sections preparatory to opening and flattening such lengths or sections for the production of window glass.

10 15 Very often a cylinder is drawn which is thicker on one side than on the other side. If, under such conditions, an ordinary electrically heated cracking wire is used the heat applied through the wire will cause the 20 thin side of the cylinder to be burnt, producing checks or flaws, while the thick side of the cylinder is not heated sufficiently for a cracking off action. If, under such conditions, the thick side of the cylinder should 25 be heated sufficiently to crack off, the imperfections produced, as a result of an irregular cracking off action when the walls of the cylinder are of uneven thickness, are liable to cause the cylinder to break or 30 "blow up" when the cylinder is handled or placed in the flattening oven. All prior cracking devices with which I am familiar, using an electrical heat resistance or cracking wire, are open to these objections and 35 deficient in that they do not permit proper application of the electric current to compensate for variations in the thickness of different portions of the cylinder.

One object of my invention is to provide 40 an electrically heated cracking device, including a resistance wire, and current controlling connections, whereby the current may be supplied to heat the entire wire or to heat only a portion of the wire at will, thus 45 enabling the operator to apply the heat to the cylinder to compensate for variations in the thicknesses of different portions thereof.

A further object of the invention is to 50 provide a cracking wire which will admit of the application of heat first to the thick side of a cylinder so that the same may be partially burnt through, and then to all portions of the cylinder encircled by the wire simultaneously, allowing a clean cracking action 55 to be performed with an avoidance of liability

of checking, "blowing-up" or irregular breaking of the cylinder.

The invention consists of the features of construction, combination and arrangement of parts, hereinafter fully described and 60 claimed, reference being had to the accompanying drawing, in which:—

Figure 1 is a cross section through a cylinder showing the application of my improved cracking device.

Figure 2 is a detail section through the junction piece.

Figure 3 is a diagram of the resistance wire and its electric circuit connection.

Figure 4 is a sectional view through the 70 switch block.

In carrying my invention into practice I provide a cracking device comprising an electrically heated resistance wire 1 of circular form to embrace the glass cylinder 2. 75 This wire is divided into sections 3 and 4, which may be equal or unequal as desired or as circumstances may require. The wire is arranged in an electric circuit including a negative conductor 5 and a positive conductor 6 supplied with current from any suitable source.

At one side of the wire the ends of the sections 3 and 4 are passed through openings in spaced metallic plates 6' and through corresponding openings in a junction block or piece 7, to which said plates are secured, as by means of screws 8, and then connected with the negative wire 5, thus coupling the wire sections to the negative conductor for 90 the passage of current through either or both of said wire sections and said conductor. The opposite ends of the wire sections 3 and 4 are similarly passed through openings in metallic plates 9 secured to one end 95 of a hand piece 10 forming a switch block, to the opposite end of which hand piece the positive conductor 6 is connected. From the plates 9 the wires 3 and 4 extend through channels in the block 10 to contacts 9' arranged in proximity to the conductor 6. Each block 7 and 10 is made of fiber or other suitable non-conducting material, allowing the same to be safely handled and which serve in insulating the metallic plates thereon and portions of the wire connected therewith from each other.

Carried by the block or hand piece 10 is a four-position rotary snap switch, including a knob or finger piece 11 and a switch 110

blade or plate 11', which is adjustable to cut off the supply of current through the cracking wire and to regulate the passage of current therethrough. This switch has a blank 5 or cut off position, in which blade 11' is free from engagement with both contacts 9', a second position in which the blade connects the positive conductor 6 solely with one of the contacts 9' and the cracking wire section 10 3 leading thereto exclusive of the cracking wire section 4, a third position in which it connects the positive conductor 6 solely with the other switch contact 9' and the cracking wire section 4 leading thereto exclusive of 15 the cracking wire section 3, and a fourth position in which it connects both contacts 9' and both cracking wire sections 3 and 4 with the conductor 6. Thus it will be understood that by adjustment of the switch 11 current 20 may be supplied through one cracking wire section without passing through the other cracking wire section, which remains dead or negative, and that by adjustment of said switch both cracking wire sections may be 25 connected with the conductor 6 for the passage of current entirely through and around the cracking wire, and that both cracking wire sections may be thrown out of circuit at any time by movement of the switch to 30 its blank position.

In practice, the conducting wire 5 and the block 7 to which the minus ends of the cracking wire section 3 are connected are preferably arranged so as to come at the 35 rear of the glass cylinder, and so that the hand piece 10 carrying the switch 11, and to which the positive conductor 6 is connected, will be arranged at the front of the cylinder, which will be supported for the 40 severing operation in the usual horse or cradle. The ends of the wire which are connected with the block 10 may be so fastened to said block that either or both of them may be detached therefrom so that the cracking 45 wire may be applied in position and removed after use and adjusted about the cylinder to closely hug the same for the cracking operation. As shown in the present instance, the 50 wire sections 3 and 4 are of unequal lengths, that is form long and short arcs of a circle, thus allowing the hand piece 10 to be arranged in a convenient horizontal position at the front of the cylinder, while the junction block 7 is disposed above the horizontal center of the cylinder, and at the rear thereof, for the connection of the conductor 6 with an overhead source of electric supply if desired. By the construction described it will 55 be seen that if the cylinder is of uniform thickness throughout the switch 11 may be adjusted for the simultaneous passage of current through both wire sections 3 and 4, whereby the cylinder will be uniformly heated around the cracking line for a uniform cracking action. If, however, the 60

cylinder should be thicker on one side than on the other side, as, for example, thicker on the side embraced by the wire section 3, current may be passed through said wire section 3 to partially cut through the cylinder, and then the current may be passed through both wire sections 3 and 4 to crack the cylinder uniformly all around. By this means a cylinder of uniform thickness may be cracked in one operation in the usual manner, while the cylinder which is thicker at one side than the other may be cracked in two heat applying operations in such a manner as to avoid undue heating of the cylinder at the thin side and liability of 75 breakage of the cylinder from the unequal application of heat or other well known causes.

Having thus fully described my invention, I claim:—

1. An electrical cylinder cracking device comprising a cracking wire to embrace the cylinder, said wire being formed of electrically insulated sections, current supplying means, and means for directing the electric current through one section of the wire exclusive of another section thereof. 85

2. An electrical cracking device comprising a cracking wire to embrace the cylinder, said wire being made of a pair of sections electrically insulated from one another, means for connecting like ends of the wire sections to one conductor of an electric supply circuit, and a switch device for connecting the other ends of the wire to the other conductor of said supply circuit, said switch device being operative to cut off the supply of current from both sections of the wire or to direct the current for passage through either one of the wires independently of the other or simultaneously through both sections of the wire. 95

3. An electrical cylinder cracking device comprising a cracking wire formed of two electrically insulated sections adapted to be respectively arranged to bear upon thick and thin portions of a cylinder, a source of electric current supply, and means for directing the current whereby the current may be caused to pass exclusively through the wire section bearing against one portion of the cylinder and thereafter through both wire sections simultaneously. 110

4. An electrical cylinder cracking device comprising a cracking wire, means insulating portions of the wire from each other, and means for passing a current through one portion of the wire independent of another. 120

5. An electrical cylinder cracking device comprising a cracking wire to embrace the cylinder, said wire being formed of sections, means connecting the ends of the wire sections at one side of the wire with one conductor of an electric circuit, and means for connecting the ends of the wire sections at 125 130

the opposite side of said wire with the other conductor of an electric circuit, said latter-named means including a switch for cutting off the current from said wire or for causing the current to pass through either wire section independently or through both wire sections jointly.

6. An electrical cylinder cracking device comprising an electrical resistance conductor wire adapted to be passed around a cylinder and including a plurality of electrically insulated portions, and means for passing a heating current through one por-

tion of the wire independent of another portion thereof.

7. An electrical cylinder cracking device comprising an electrical resistance conductor wire adapted to be passed around a cylinder and including at least two electrically insulated portions, and means for passing a current through one of said portions independent of the other or others of said portions or of passing the current through the entire wire.

In testimony whereof I affix my signature. 25
WILLIAM WESTBURY.
